DESIGN FOR AN ARTIFICIAL BAIT OR SIMILAR ARTICLE

Edward L. Jacobs, Vicksburg, Mich.

Application December 29, 1941, Serial No. 104,902

Term of patent 14 years

To all whom it may concern:

Be it known that I, Edward L. Jacobs, a citizen of the United States of America, residing at Vicksburg, county of Kalamazoo, and State of Michigan, have invented a new, original, and Ornamental Design for an Artificial Bait or Similar Article, of which the following is a specification, reference being had to the accompanying drawing, forming a part thereof wherein:

I claim:

The ornamental design for an artificial bait or similar article, as shown.
